United States Patent Office

Des. 194,728
Patented Feb. 26, 1963

194,728

CONFECTION

Martin J. Ferguson, 22 Purchase St., Rye, N.Y.

Filed Mar. 15, 1962, Ser. No. 69,281

Term of patent 14 years

(Cl. D82—2)

FIG. 1 is a rear perspective view of a confection embodying my new design.

FIG. 2 is a front elevational view of the same.

FIG. 3 is a side elevational view of the same.

FIG. 4 is a top plan view of the same.

FIG. 5 is a bottom plan view of the same.

I claim:

The ornamental design for a confection, as shown.
